UNITED STATES PATENT OFFICE

125,030

DESIGN FOR A DISPLAY CASE

Paul M. Ressinger, Chicago, Ill.

Application August 30, 1940, Serial No. 94,729

Term of patent 3½ years

To all whom it may concern:

Be it known that I, Paul M. Ressinger, a citizen of the United States, residing at Chicago, in the county of Cook and State of Illinois, have invented a new, original, and ornamental Design for a Display Case, of which the following is a specification, reference being had to the accompanying drawings, forming a part thereof, and in which

Fig. 1 is a front perspective view of a display case, showing my new design;

Fig. 2 a top plan view; and

Fig. 3 is a rear perspective view thereof.

I claim:

The ornamental design for a display case, as shown.

PAUL M. RESSINGER.
